UNITED STATES PATENT OFFICE.

OSWALD H. HANSEN, OF PORT WASHINGTON, WISCONSIN, ASSIGNOR TO GILSON MANUFACTURING COMPANY, OF PORT WASHINGTON, WISCONSIN, A CORPORATION OF WISCONSIN.

CHAIR SPRING.

Application filed April 16, 1921. Serial No. 461,829.

To all whom it may concern:

Be it known that OSWALD H. HANSEN, a citizen of the United States, residing at Port Washington, in the county of Ozaukee and State of Wisconsin, has invented a certain new and useful Chair Spring, of which the following is a specification.

This invention relates in general to improvements in the art of manufacturing and 10 of operating resilient restraining elements, and relates more specifically to improvements in the construction and manipulation of helical cushioning springs for tilttable chairs and the like.

15 A general object of the invention is to provide an improved spring structure which is simple in construction and efficient in operation.

It is customary, in the construction of 20 tilttable office chairs of different types, to utilize helical springs of either the tension or compression type, for the purpose of cushioning the backwardly tilting seat and to return the seat to normal position. The 25 helical tension springs now universally employed, are costly to manufacture because the opposite ends of the springs are bent into loops which are pivotally attached to the relatively tilttable chair iron members, 30 these looped supporting ends frequently breaking thereby necessitating replacement of the entire springs. The pivoted tension springs although costly and subject to frequent renewal on account of breakage, do 35 not bend laterally due to transverse angular displacement of the pivotal end supports, because these pivotal supports accommodate such angularity and always maintain the longitudinal spring axis rectilineal. The 40 helical compression springs now universally employed, are relatively inexpensive to manufacture as they may be cut to suitable lengths from a continuous helical spring of proper diameter, and no distortion of the 45 spring ends is necessary. These compression springs when applied to chairs, are ordinarily set between cast iron sockets fastened to the relatively tilttable chair iron members, 50 the sockets serving to retain the springs in place and to prevent rotation of the springs about their longitudinal axes. The helical compression springs are however subject to objectionable transverse bending during the 55 tilting and return movements of the seat, due to the relative transverse angular dis-

placement of the sockets with respect to the longitudinal spring axes. This transverse bending of the springs weakens the same and causes them to break, thereby also necessitating frequent spring renewal. Both of 60 these prior forms or types of helical springs also are objectionable because they become squeaky when not sufficiently lubricated, due to the relatively great transverse angular displacement of the spring end supports with 65 respect to the longitudinal spring axes, which exists in practically all of the present commercial chair irons.

A more specific object of the present invention is to provide an improved compression spring for tilttable chairs and for similar service, which may be manufactured at minimum cost and in which transverse bending of the spring with respect to its longitudinal axis, is positively eliminated regardless of the extent of transverse angular displacement of the spring end supports. Another specific object of the invention is to provide a helical compression spring which may be readily substituted for the standard 70 tension springs now employed in many of the commercial chair irons, without necessitating alteration of these irons. A further object of the invention is to avoid necessity of utilizing expensive cast end sockets for 75 springs of the compression type, by substituting relatively inexpensive sheet metal stampings which will effectively support the spring and which will prevent rotative displacement thereof about its longitudinal 80 axis. Still another object of the invention is to provide a simple and convenient method of inserting and removing chair springs. These and other objects of the invention 85 will be apparent from the following description.

Some of the novel features of chair construction disclosed but not specifically claimed herein, form no part of the present invention and constitute the subject matter 90 of application Serial Number 424,015, filed November 15, 1920.

A clear conception of an embodiment of the invention and of the operation of a device constructed in accordance therewith, 95 may be had by referring to the drawing accompanying and forming a part of this specification, in which like reference characters designate the same or similar parts in the various views.

Fig. 1 is a fragmentary part sectional side elevation of a tiltable revolving chair having an improved spring structure embodied therein.

5 Fig. 2 is a bottom view, partly in section, of the upper portion of the chair support which is attached directly to and is rotatable with the seat, showing the improved spring structure embodied therein.

10 Fig. 3 is a longitudinal vertical section through the improved spring structure.

Fig. 4 is an end view of the improved spring structure.

15 Fig. 5 is an end view of the front spring structure support.

The tiltable revolving chair disclosed in Fig. 1, comprises generally a base, a vertical standard 4 having its lower extremity rigidly secured to the base, a manually adjustable nut 14 secured to the standard 4, a bracket 5 supported upon the nut 14 and freely rotatably mounted upon the upper portion of the standard 4, an inverted U-shaped spreader 7 horizontally pivotally

20 mounted upon the bracket 5, spider arms 3 rigidly secured to the upper side portions of the spreader 7 and a seat 2 attached to the front and rear ends of the spider arms 3.

25 The chair base comprises four legs 33 extending radially away from the lower extremity of the standard 4, top and bottom plates 31 secured to the standard 4 and engaging upper and lower portions of the legs 33, and filler blocks 32 located in the

30 corners formed by the coacting inner leg ends. The central vertical standard 4 which has its lower extremity rigidly secured to the chair base, has its upper portion screw threaded and provided with a longitudinal recess.

35 The manually adjustable nut 14 has a central bore provided with screw threads which coat with the threads on the standard 4, and is further provided with a locking pin 17 engageable with the longitudinal recess of the standard 4 to lock the nut 14 in an adjusted position against movement relative to the standard. The upper central portion of the nut 14 is provided

40 with an annular recess within which a bearing element 15 may be located. The main bracket 5 which is freely rotatably mounted upon the upper portion of the standard 4, has an elongated upright hub which is

45 bored to receive the standard 4 and which is provided at its lower extremity with a flange coacting with the bearing element 15. The nut 14 is provided with one or more inwardly projecting retaining lugs 16 which extend over the lower bracket flange

50 and prevent axial separation of the nut 14 and bracket 5. The bracket 5 has a forwardly projecting arm 6 the lower rear portion of which is provided with a pair of spaced downwardly extending parallel lugs, and the forward upper extremity of

55 which is bored to receive and to support a spring adjusting bolt 10. The upper extremity of the hub of the bracket 5 is provided with an abutment 23, while a medial portion of the bracket arm 6 is formed with a pair of opposed lugs providing abutments 25. The inverted U-shaped spreader 7 is preferably made of sheet metal and has its lower side walls pivotally connected to the downwardly extending bracket lugs by 70 means of a horizontal transverse pivot pin 13 which may be riveted to the spreader. The spreader 7 is oscillatory about the pivot pin 13 and transversely of the standard 4, and has an upper abutment 22 which is engageable with the bracket abutment 23 to limit the rearward swinging movement of the spreader 7 and seat 2. The lower front surfaces 24 of the spreader side walls are engageable with the upper rear surfaces 80 of the abutments 25 to limit the forward swinging movement of the spreader 7 and seat 2.

75 The spreader 7 and the parts associated therewith, are at all times urged forward toward the bracket abutments 25, by means of a pair of laterally spaced helical compression springs 8. The springs 8 are identical in structure and are formed by cutting a long coil of spring rod or wire into suitable lengths and without distorting the ends of the wire. The opposite ends of each spring 8 terminate adjacent to a central longitudinal plane of the spring 8. Within each spring 8 is located a pair of T-shaped tension plates or members 18, 19 which are identical in structure and which are preferably formed of sheet metal with the aid of dies. Each of the T-shaped tension members 18, 19 consists of an elongated portion extending longitudinally through and in close proximity to the upper and lower inner surfaces of the spring 8, the elongated portions having transverse end projections 90 engaging side surfaces of the spring wire and coacting with the adjacent extreme end of the spring to prevent rotation of the coil about its longitudinal axis. The end of each tension member 18, 19 upon which the projections 20 are formed, is also provided with a central recess 21 for permitting full expansion of the spring 8 without interfering with the relatively movable spring supporting elements. The front and rear protruding ends of the tension members 18, 19 are provided with suspension holes which may be of any desired shape. The holes of the forwardly projecting tension members 19 are engaged by the end portions 28 of the spring supporting block 9, while the holes of the rearwardly projecting tension members 18 are engaged by the transverse spring supporting pin 12. The block 9 is adjustably secured to the bracket arm 6 by means of an adjusting bolt 10 having a 100

105

110

115

120

125

130

square portion 20 fitted within a square hole in the block, and an adjusting nut 11 which has screw thread coaction with the bolt thereby serving to vary the degree of compression of the springs 8. The block 9 is provided with eccentric end portions 26 and cylindrical central medial portions 27 connected with the end portions 26 by means of the elliptical portions 28, see Figs. 2, 3 and 5. The ends of the pin 12 are recessed at the portions 29 thereof, these recessed portions 29 coacting with the spreader side walls to prevent endwise displacement of the pin 12, as shown in Fig. 2.

15 During normal use of the chair, the seat 2, spider arms 3, spreader 7 and bracket 5 are free to be revolved about the standard 4 and upon the bearing element 15, without varying the height of the seat. The weight 20 of these revoluble elements and of an occupant of the chair, is supported by the base structure through the intervening standard 4 and nut 14. The chair seat and spreader 7 may be tilted rearwardly at will until the 25 upper spreader abutment 22 engages the upper bracket abutment 23, the springs 8 being compressed during such tilting and the members 18, 19 being subjected to tensional stresses. Upon release of the seat 2, after 30 having been tilted, the springs 8 expand and swing the spreader 7 forwardly until the abutment surfaces 24 engage the bracket abutments 25. In order to insure such return movement of the seat 2, the springs 8 35 are placed under initial compression by manipulation of the adjusting nut 11.

If it is desired to vary the height of the chair seat 2, it is necessary to release the locking pin 17 and to rotate the adjusting nut 14 relatively to the stationary standard 4. The nut 14 will then travel along the standard 4 to the desired position of adjustment, when it may be again locked to the standard by allowing the end of the pin 17 45 to snap into the longitudinal recess of the standard 4. The springs 8 may be readily removed by unscrewing the adjusting nut 11, whereupon the tension members 19 will be moved rearwardly until the pin 12 enters the recesses 21 of these members, and the portions 28 of the block 9 enter the recesses 21 of the tension members 18. The springs 8 will then have been entirely relaxed, and the supporting pin 12 is free to be rotated 50 180 degrees and removed from the openings in the side walls of the spreader 7. The tension members 19 may then be removed over the eccentric end portions 26 of the block 9 and the pin 12 may be removed from the 55 openings in the protruding ends of the members 18, whereupon the tension members 18, 19 may be freely endwise removed from the springs 8. It will thus be noted that the 60 spring adjustment and removal may be readily accomplished.

It will also be noted that the springs 8 may be manufactured at minimum cost and that the members 18, 19 positively prevent transverse bending of the springs 8 with respect to their longitudinal axes. The 70 spring element disclosed in Figs. 3 and 4, and comprising a compression spring 8 and a pair of tension members 18, 19, may be readily substituted for a standard tension spring having hooked ends. The tension 75 members 18, 19 may be constructed of sheet metal with the aid of dies, thereby minimizing the cost of manufacture thereof. The members 18, 19 besides serving to compress the springs 8, also prevent rotation of the 80 springs about their longitudinal axes by providing abutments for the spring wire ends.

It should be understood that it is not desired to limit the invention to the exact details of construction and of operation herein 85 shown and described, for various modifications within the scope of the claims may occur to persons skilled in the art.

It is claimed and desired to secure by Letters Patent:—

1. A spring for tilting chairs comprising, a helical compression spring having substantially circular coils, and a tension member engaging each end coil of said spring, each of said members abutting an extreme end 95 of said spring to prevent rotative movement of said spring about its longitudinal axis.

2. A spring for tilting chairs comprising, a helical spring having substantially circular coils, and a T-shaped member forming a transverse abutment for each extreme end of said spring to prevent rotation of said spring about its longitudinal axis, said members engaging the opposite end coils of and extending longitudinally through said spring 100 in opposite directions.

3. A spring for tilting chairs comprising, a helical spring having substantially circular coils, and a pair of members engaging the opposite end coils of and extending longitudinally through said spring, each of said members having a transverse projection abutting an extreme end of said spring to prevent rotation of said spring about its 110 longitudinal axis.

4. A spring for tilting chairs comprising, a spring formed of a coiled rod having ends terminating on opposite sides of a longitudinal central plane of the spring, and a pair of tension members engaging the opposite end coils of said spring and abutting the extreme ends of said rod to prevent rotation of said spring about its longitudinal axis.

5. In combination, a standard, a bracket pivotally mounted upon said standard, a spreader pivoted to said bracket in front of said standard, a tension member secured to said bracket in front of said standard, a tension member secured to said spreader in front of said standard, and a helical compres- 125 130

tion spring having its opposite end coils engaging said members and its opposite ends abutting against said tension members to prevent rotative movement of said spring about its longitudinal axis.

6. A spring for tilting chairs comprising, a helical compression spring, and a tension member engaging each end coil of said spring, each of said members abutting an extreme end of said spring to prevent rotative movement of said spring about its longitudinal axis.

7. In combination, a standard, a bracket mounted upon said standard, a spreader pivoted to said bracket in front of said standard, a tension member pivoted to said spreader in front of said standard and vertically above said spreader pivot, a tension member secured to said bracket in front of the pivot of said spreader supported tension member, and a helical spring embracing and compressible between said tension members.

8. In combination, a standard, a bracket mounted upon said standard, a spreader pivoted to said bracket in front of said standard, a tension member pivoted to said bracket in front of said standard, a tension member pivoted to said spreader in front of said standard, and a helical compression spring embracing and compressible between said tension members.

9. In combination, a standard, a bracket mounted upon said standard, a spreader mounted upon said bracket, a tension member secured to said bracket, a tension mem-

ber secured to said spreader, and a helical compression spring embracing and compressible between both of said tension members.

10. In combination, a standard, a bracket mounted upon said standard, a spreader mounted upon said bracket, a tension member secured to said bracket, a tension member secured to said spreader, and a helical compression spring compressible by said members and having opposite ends abutting against said tension members to prevent rotative movement of said spring about its longitudinal axis.

11. In combination, a standard, a bracket pivotally mounted upon said standard, a spreader pivotally mounted upon said bracket, a tension member secured to said bracket, a tension member secured to said spreader, and a helical compression spring embracing and compressible by both of said tension members and having opposite ends abutting against said members to prevent rotative movement of said spring about its longitudinal axis.

12. In combination, a standard, a bracket mounted upon said standard, a spreader mounted upon said bracket, a helical compression spring, and a tension member engaging each end of said spring and extending longitudinally therethrough, said tension members being secured to said bracket and to said spreader respectively.

In testimony whereof, the signature of the inventor is affixed hereto.

Oswald H. Hansen.
